CLAIM

The ornamental design for a toy figurine, as shown and described.

DESCRIPTION

FIG. 1 is a front perspective view of a toy figurine showing the new design;

FIG. 2 is a front elevational view of the toy figurine of FIG. 1; FIG. 3 is a rear elevational view of the toy figurine of FIG. 1; FIG. 4 is a side elevational view of the toy figurine of FIG. 1, the opposite side elevational view being a mirror image; FIG. 5 is a bottom plan view of the toy figurine of FIG. 1; and, FIG. 6 is a top plan view of the toy figurine of FIG. 1. The broken lines are for environmental and illustrative purposes only and are not part of the claimed design.
